UNITED STATES PATENT OFFICE.

THOMAS SHAW, OF PHILADELPHIA, PENNSYLVANIA.

FIRE-ALARM.

SPECIFICATION forming part of Letters Patent No. 243,984, dated July 5, 1881.

Application filed May 16, 1881. (No model.)

To all whom it may concern:

Be it known that I, THOMAS SHAW, of the city and county of Philadelphia, Pennsylvania, have invented a new and Improved Process of 5 Automatically Detecting Undesirable Fires over Large Areas of Buildings, Sheds, &c.; and I hereby declare the following to be a full, clear, and exact description of the same, reference being had to the accompanying drawing, 10 and to the letters of reference marked thereon.

My invention relates to that class of fire-alarms in which a combustible cord, when burned, serves as a means of creating an alarm; and my invention is a simple, cheap, and effective apparatus, whereby the alarm is given when 15 tension is removed from the cord.

The drawing shows the improved device, *d* being the cord, which is attached at one end, *i*, to a wall or other object, and *k* a weight suspended from the other end.

The alarm is of any suitable character, as a 20 train of wheels and gong, a whistle, cartridge, or any of the well-known devices, which is set, wound up, or otherwise prepared for operation, and is held in action by a detent consisting of a spring-plate, *g*, attached at one end to a block, *a*, the other end affording a bearing 25 for a lug, which may be on a disk, *o*, upon a shaft of the gear-train, or upon any other part 30 of the alarm mechanism, so that when the plate *g* is moved from the lug the train will be set in operation and sound an alarm.

The tendency of the spring is to withdraw 35 the plate from the lug; but the rope *d*, passing over a pulley, *e*, supported between ears on the

plate, so long as it supports the weight *k*, serves to draw out the plate to the position shown, a pin, *h*, in the plate, passing through a hole in the block *a*, and provided with a head or enlargement, serving as a means of limiting the 40 outward movement of the plate. The rope is conducted to those points where it will be most likely to be burned should a fire occur, and as soon as it is thus severed all draft upon the plate will be removed, and it will spring back, 45 releasing the alarm mechanism.

To secure a signal to a distant point the plate *g* may connect with an electric wire, *m*, and an electrode, *f*, connects with another, and is arranged so that the circuit is complete when 50 the plate and electrode are in contact, and a current transmitted to an electric alarm.

I claim—

1. The combination, in a fire-alarm, of an alarm device, substantially as described, a 55 spring-plate, *g*, arranged as a detent for the alarm device, and a cord, *d*, connected to the plate, as specified, to hold it in position so long as the cord is taut, substantially as set forth.

2. The combination of alarm mechanism, 60 spring-detent plate *g*, carrying a roller, *e*, and weight *i*, as set forth.

3. The combination of the alarm mechanism, spring-detent plate *g*, roller *e*, cord, weight *k*, electrode *f*, and wires *l m*, as specified.

THOMAS SHAW.
